UNITED STATES PATENT OFFICE.

THOMAS A. KEEFER, OF DAYTON, OHIO, ASSIGNOR TO THE RECORDING DEVICES COMPANY, OF DAYTON, OHIO, A CORPORATION OF OHIO.

LOCK.

1,309,438.

Specification of Letters Patent.

Patented July 8, 1919.

Application filed November 30, 1917. Serial No. 204,486.

To all whom it may concern:

Be it known that I, THOMAS A. KEEFER, a citizen of the United States, residing at Dayton, in the county of Montgomery and State 5 of Ohio, have invented certain new and useful Improvements in Locks, of which the following is a specification, reference being had therein to the accompanying drawings.

This invention relates to locks and is a 10 modification of the device shown, described, and claimed in the application filed by me of even date herewith, Serial No. 204,487.

The object of the invention is to provide 15 a controlling device for the bolt actuating mechanism of a lock, such as is described in the above-mentioned application, which will be controlled by the movement of the bolt actuating device in either direction; and which will also serve to lock the key 20 against removal until the actuating mechanism has completed its movement in one direction or the other.

Further, it is an object of the invention 25 to provide such a device which will be very simple in its construction, and will comprise but a few parts.

In the accompanying drawings Figure 1 30 is a vertical sectional view taken centrally through a controlling member embodying my invention; Fig. 2 is an elevation of the 35 mechanism shown in Fig. 1; and Fig. 3 is a detail view on a slightly reduced scale of the connections between the bolt actuating shaft and the bolt.

35 In these drawings I have illustrated one embodiment of my invention and have shown the same in a form designed for use in a recording lock. It will be understood that this particular form is chosen for the 40 purpose of illustration only and that the mechanism, and more particularly the bolt actuating mechanism, may be of any suitable character which will operate the bolt when said mechanism is moved in either 45 one of two directions.

In that form of the invention here illustrated I have shown the device as mounted on the outer side of the door 1, and as carried by an escutcheon, or supporting structure, which in the present instance comprises an outer housing, or casing, 2, preferably of bronze, and an inner supporting plate 3 rigidly secured to the housing and forming a support for the mechanism. The bolt 55 actuating mechanism may, as has been

stated, be of any suitable form, but as here shown it comprises a bolt actuating shaft 4 which is rotatably mounted in the supporting plate of the escutcheon and is provided on the opposite side of the door with means 60 for operatively connecting the same with a bolt 5. This means, as shown in Fig. 3, consists of an actuating plate 6 rigidly secured to the shaft 4 and having arms 7 and 8 arranged on opposite sides of a stud 9 carried by the bolt, so that the movement of the shaft and the actuating plate in one direction will cause one arm to engage the stud on the bolt and project the bolt, and the movement of the shaft and the operating plate in the opposite direction will cause the other arm to engage the stud and retract the bolt. Suitable locking devices are provided to prevent the movement of the bolt 65 independently of the actuating devices, but 70 these locking devices form no part of the present invention, and need not be here described. The outer end of the shaft 4 is provided with an operating member, such as a knob 10, which is here shown as journaled 75 in the escutcheon and as having its trunnion, 11, provided with a longitudinal bore into which the end of the shaft projects. The connection between the shaft and the trunnion is such as to cause these parts to 80 rotate together but to permit them to be readily separated when the escutcheon is removed, and in the present instance the end of the shaft 4 is provided with a slot 12 adapted to receive a pin 13 mounted in the 85 trunnion of the knob and extending through the bore thereof.

The controlling, or locking, devices for the bolt actuating mechanism may take various forms but I prefer, for the present 90 type of lock, that here illustrated, in which a disk 14 is rigidly connected with the shaft 4 of the bolt operating mechanism. In the present construction this disk is rigidly secured to a collar, or hub, 15, which in turn 95 is secured to the trunnion 11 of the operating knob, preferably by means of the pin 13 which extends through the bore of the trunnion, thus causing the knob, the shaft and the disk to rotate in unison. Coöoperating 100 with the disk 14 is the controlling device proper, which is here shown in the form of a plate 16 having a part coöperating with the disk to lock the same against movement in either direction. Preferably this part is 105 110

in the form of a lug 17 projecting from that end of the plate 16 adjacent to the disk and adapted to enter a notch 18 formed in the periphery of the disk, and so arranged there-
5 in that when the bolt operating mechanism is in its normal or home position this notch will lie in alinement with the lug 17. In the construction here illustrated the locking member 16 is spring actuated so that it is
10 held normally in operative relation to the disk and is automatically returned to that position when it is released after having been moved to an inoperative position. This is accomplished by means of a spring 19
15 secured at one end to the controlling member and connected at its other end with a pin 20 secured to the supporting plate 3 and extending through an opening in the controlling member. Key actuated means
20 are provided for moving the controlling member to an inoperative position with relation to the bolt actuating mechanism and as here shown the controlling member 16, which is slidably mounted upon the sup-
25 porting plate 3, is provided with an opening 21 in which is mounted an actuating member 22. This actuating member is operated by the key and, in the present instance, I have shown the same as rigidly secured to the in-
30 ner end of a key barrel 23 forming part of a cylinder lock of a well known construction. The insertion of the key in the key barrel releases the same for rotation and the actuating device 22 is of such a character that
35 the movement of the key, which can turn in one direction only, will cause it to actuate the controlling member 16, and the actuating device and the controlling member have parts which coöperate to lock them in the
40 positions to which they are moved by the key. Inasmuch as the key can be removed from the key barrel only when the latter is in its home or normal position it will be locked in the barrel until the actuating de-
45 vice has been released. As here shown the actuating device is in the form of a disk having a cam-shaped portion or nose, 24, the lower edge of which is so arranged that when the actuating device is in its normal
50 position this edge will be substantially parallel with the lower edge of the opening 21 in the controlling member, and will act upon this edge of the opening to impart move-
55 ment to the actuating member when the key actuated device is rotated. A spring 25 coiled about the hub of the key actuated disk 22 and connected with the supporting plate 3 tends to move the disk and the key barrel toward their home or normal positions. The
60 lower edge of the opening 21 in the control-
65 ling member is provided with a shoulder 26 and the movement of the key actuated device will carry the nose 24 thereof past this shoulder and permit the controlling member to be moved by its spring a distance suffi-

cient to carry the shoulder into the path of the nose without permitting the lug 17 to enter the notch in the disk 14 of the bolt actuating mechanism, thereby locking both the disk and the controlling member in the 70 positions to which they have been moved. A second nose 27 on the key actuated disk is arranged to engage a shoulder 28 formed in the upper edge of the opening 21 of the controlling member to limit the movement of 75 the key actuated disk by the key.

Means are provided which will be actuated by the movement of the bolt actuating mechanism to disengage the controlling member from the key actuated device and 80 permit these parts to return to their normal positions upon the completion of the movement of the bolt actuating mechanism. Preferably this means is embodied in the notched disk 14, and, as here shown, this disk 85 is provided on opposite sides of the notch 18 therein with cam-shaped portions 29, one or the other of which will engage the lug 17, when the shaft 4 is rotated in either direc-
90 tion, and will move the controlling member 16 downward far enough to move the shoulder 26 out of the path of the cam nose 24 of the key actuated device, thus permitting this device to be returned to its normal position, and further permitting the controlling mem-
95 ber to be held by its spring in engagement with the edge of the disk until the latter is returned to its normal position so that it will enter the notch in the disk when the latter has completed its return movement. The disk 14 is further provided at the outer 100 end of each cam-shaped portion with a shoulder 30, to engage the lug 17 and posi-
105 tively limit the movement of the bolt actuating mechanism. In order to prevent the return of the bolt actuating mechanism to its normal or home position before it has made a complete operative movement in one direction, I have provided a full-stroke de-
110 vice which comprises a tapered pawl 31 held 110 normally in a central position by a spring 32 and adapted to ride over ratchet teeth 33 formed in the edge of the disk 14 on oppo-
115 site sides of a central notch 34, in which the pawl normally lies. Beyond each toothed portion of the disk the latter is provided with other notches 35 to receive the nose of the pawl and permit the latter to change its position so it can ride over the teeth upon the return movement of the disk. 120

The operation of the mechanism will be readily understood from the foregoing description and it will be apparent that I have provided a very simple and highly efficient controlling mechanism for the bolt actuating 125 mechanism, which comprises a very few parts and which will be controlled by the movement of the bolt actuating mechanism in either direction.

While I have shown and described one em- 130

bodiment of my invention I wish it to be understood that I do not desire to be limited to the details thereof as various modifications will occur to a person skilled in the art.

5 Having now fully described my invention, what I claim as new and desire to secure by Letters Patent, is:—

1. In a lock, bolt actuating mechanism having operative movement in two directions, a controlling device movable into and out of a position to lock said mechanism against operative movement in either direction, a key actuated device to move said controlling device into an inoperative position, and means controlled by the movement of said actuating mechanism in either direction to automatically return said controlling device to its operative position.

2. In a lock, bolt actuating mechanism having operative movement in two directions, a controlling device movable into and out of a position to lock said mechanism against operative movement in either direction, a key actuated device to move said controlling device into an inoperative position and to retain the same in that position, and means controlled by the movement of said actuating mechanism in either direction to release said controlling device and permit it to return to its operative position.

3. In a lock, bolt actuating mechanism having operative movement in two directions, a controlling device movable into and out of a position to lock said mechanism against movement in either direction, a spring to hold said controlling device normally in locking relation to said actuating mechanism, a key actuated device to move said controlling device against the tension of said spring, said devices having coöperating parts to retain them in the positions to which they have been moved, and means actuated by the movement of said actuating mechanism in either direction to automatically disconnect said parts and permit said devices to return to their normal positions.

4. In a lock, bolt actuating mechanism having operative movement in two directions, a controlling device comprising a single member movable into and out of a position to lock said mechanism against operative movement in either direction, a key actuated device to move said controlling device into an inoperative position, and means controlled by the movement of said actuating mechanism in either direction to automatically return said controlling device to its operative position.

5. In a lock, bolt actuating mechanism having operative movement in two directions and comprising a notched disk, a controlling member having a part movable into and out of the notch in said disk, a spring acting upon said controlling member to hold the same in said notch, a key actuated de-

vice to act upon said member to move said part out of said notch and to retain the same in an inoperative position, and parts carried by said disk on opposite sides of said notch to engage said controlling member, to actuate the same and impart movement thereto to disengage it from said key actuated device.

6. In a lock, bolt actuating mechanism having operative movement in two directions and comprising a notched disk, a controlling member having a part movable into and out of the notch in said disk, a spring acting upon said controlling member to hold the same in said notch, a key actuated device to act upon said member to move said part out of said notch and to retain the same in an inoperative position, said disk having cam-shaped portions on opposite sides of said notches to engage that part of said controlling member which has been withdrawn from said notch and move the controlling member in a direction to disengage it from said key actuated device upon the completion of the operative movement of said bolt actuating mechanism in either direction.

7. In a lock, bolt actuating mechanism having operative movement in two directions and comprising a notched disk, a controlling member having a part movable into and out of the notch in said disk, a spring acting upon said controlling member to hold the same in said notch, a key actuated device to act upon said member to move said part out of said notch and to retain the same in an inoperative position, said disk having cam-shaped portions on opposite sides of said notch to engage that part of said controlling member which has been withdrawn from said notch and move the controlling member in a direction to disengage it from said key actuated device upon the completion of the operative movement of said bolt actuating mechanism in either direction.

8. In a lock, bolt actuating mechanism having operative movement in two directions and comprising a notched disk, a controlling member having a part movable into and out of the notch in said disk, a spring acting upon said controlling member to hold the same in said notch, a key actuated device to act upon said member to move said part out of said notch and to retain the same in an inoperative position, said disk having cam-shaped portions on opposite sides of said notch to engage that part of said controlling member which has been withdrawn from said notch and move the controlling member in a direction to disengage it from said key actuated device upon the completion of the operative movement of said bolt actuating mechanism in either direction, and a full-stroke device coöperat-

ing with said disk to cause it to complete its movement in one direction before it can be returned to its normal position.

9. In a lock, bolt actuating mechanism having operative movement in two directions and comprising a disk having a notch in the periphery thereof, a controlling plate mounted for reciprocatory movement toward and from said disk and having a lug 10 adapted to enter the notch in said disk, a spring tending to hold said lug in said notch, said plate also having an opening therein, a key actuated device mounted in said opening and having a part to engage 15 said plate and move the same against the

tension of said spring to withdraw said lug from said notch, said key actuated device and said plate having parts coöperating to maintain said device and said plate into positions to which they have been moved, said 20 disk also having cam-shaped portions arranged on opposite sides of said notch, one of which portions will engage said lug upon each operative movement of said bolt actuating mechanism, and will impart movement to said controlling plate to disengage the same from said key actuated device. 25

In testimony whereof, I affix my signature hereto.

THOMAS A. KEEFER.
